CLAIM

The ornamental design for a rear combination lamp for a motor vehicle, as shown and described.

DESCRIPTION

FIG. 1 is a front perspective view of a rear combination lamp for a motor vehicle showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Our design includes a mirror image of the embodiment depicted.

1 Claim, 7 Drawing Sheets
